GARAGE PRESS

Filed Sept. 8, 1925

Inventor

Robert E. Manley

By Henry H. Snelling
Attorney

UNITED STATES PATENT OFFICE

ROBERT E. MANLEY, OF YORK, PENNSYLVANIA, ASSIGNOR TO MANLEY MANUFACTURING COMPANY, OF YORK, PENNSYLVANIA, A CORPORATION OF DELAWARE

GARAGE PRESS

Application filed September 8, 1925. Serial No. 55,065.

This invention relates to presses and has for its principal object the provision of a small sturdy, inexpensive press capable of bending an object such as a crank shaft.

5 A further object of the invention lies in the provision of a cast frame particularly suitable for a press in which the cast metal of the frame is relieved of tension by means of a tension member inserted within the casting.

10 A still further object of the present invention lies in the provision of a device for conveniently operating a rack and pinion press so that the rack may be very rapidly turned 15 to proper position to start the pressure and in which the lever handle may then be moved to the most convenient position to apply the pressure irrespective of the location of the rack in the press frame.

20 In the drawings:—

Figure 1 is a side elevation of the press in its preferred form.

Figure 2 is a horizontal section taken thru the center of the cast column of the press.

25 Figure 3 is an end elevation of the rack operating means.

The main press frame is a casting 10 accurately planed at top and bottom to receive, respectively, two steel slabs 11 forming the 30 upper overhanging arm, and two somewhat longer slabs 12 forming the arm which is the bed of the press. The slabs or flats 12 are bolted as at 14 to the stand 15 which may be of any desired construction but is preferably 35 composed of the four legged base illustrated.

The frame as stated, consists of a single piece having a central vertical web 15a preferably with weight reducing openings 16 therein and bounded on top, bottom, front and 40 back by right angular flanges 17, 18, 19, and 20, respectively; the horizontal flanges 17 and 18 being rectangular, while the front and back pieces are preferably shaped, primarily for clearance when incidental equipment (not shown) is used.

The rear flange or wall 20 is solid but the front wall 19 has a groove 22 therein in which 45 preferably snugly fits a steel bolt 23 having a head 24 engaging a relatively heavy saddle piece 25 resting on the top edge of each of

the slabs 11 while the lower end of the steel bolt is threaded to receive a nut 26 engaging a saddle member 27 preferably exactly similar to the saddle 25, since the slabs 11 and flats 12 are of preferably altho not necessarily 55 exactly the same size.

While the slabs 11 are each secured to the frame by bolts 30 passing thru the integral upstanding ears 31 of the main casting 10, the entire tension stress caused by the tendency of the free ends of the arms 11 and 12 to be displaced with respect to each other when the press is in use, is borne by the steel bolt 23 which is approximately midway between the axes of the rack 34 and the rear 60 flange or side 20 of the casting, so that when the rack 34 is put under compression and the steel bolt is consequently put in tension, the casting takes compression only, this being 65 at a maximum thru the rear side 20. 70

The rack 34 slides in a block 38 bolted to the slabs 11 and carrying a cover plate 39 which confines the rack 34 in the groove in the block 38 so as to maintain the rack teeth in contact with the operating pinion 40 cut 75 on the shaft 41 which passes entirely thru the block, having at one side a handle 42 preferably held in place by a set screw 43 and having at the other end of the block a ratchet wheel 44 secured to the shaft by the pin 45. 80

The lever 50 has a socket 51 to receive the usual lever bar 52 and carries a pivot 53 for a pawl 54 which operates the ratchet 44 fast on a shaft 41. I find it very convenient to provide a pawl lock such as 60 preferably 85 threaded in the lever and adapted to engage the pawl in front or back to hold this pawl in engagement or out of engagement as desired when the pawl lock screw is screwed into the end of its travel, and freeing the pawl entirely so that the pawl may act by gravity when the lock screw 60 is moved out of engagement. The thumb screw 62 threaded thru the front plate or cover forms a ready and convenient means for locking the 90 rack in elevated position.

The press illustrated is generally used in garages and in such case the article to be straightened is supported in the usual V-blocks 70 which in turn are slidably mounted 100

on a pair of bars 71 bolted together to form a transverse support which may be adjustably secured on the flats 12 which form the bed of the press, as for example, by the stud 73 carrying a hand wheel 74 threaded thereon and engaging a small cross piece 75 straddling the flats 12. The crank or other rotatable article to be straightened is indicated at 76.

10 The size of work to be operated upon naturally varies within wide limits and it would be quite a bit of trouble to advance and lower the rack or ram by the ratchet mechanism used for the heavy leverages. The ram is therefore released by loosening the thumb screw 62 and lowered by hand to desired position against the work and this may very rapidly be done by turning the small double handle 42.

15 20 With the pawl lock now out of engagement with the pawl the lever bar 52 is raised slightly above a horizontal position, the pawl acting solely by gravity. This gives maximum convenience for applying the heavy pressure necessary to straighten an article such as an axle, and since the stroke is usually only a few degrees the lever bar can always be kept at a substantially horizontal position no matter whether the work is high or low with respect to the bed of the press.

25 30 To inspect the work the ram may be rapidly elevated and then held in raised position by the thumb screw 62 while the crank is being rotated on its V-supports while the reading for eccentricity is taken by means of the usual instruments which may be mounted in the post 77 or if these instruments are located so as not to require the raising of the ram the pawl may be locked when the lever bar is 35 40 in horizontal position and the ram may be raised the slight amount necessary by throwing over the lever bar. By having the pawl locked it is possible to raise the ram up and down as in riveting or to raise it against 45 pressure as for example when a hook is applied to the lower end of the ram for without the provision of the pawl lock there would be no means for raising the rack or ram against pressure, as the pawl would idle over the 50 ratchet. A further and important use of the pawl lock is had when a bar is to be bent but where it is desired that the bar shall not be bent by heavy pressure or a single stroke, in such cases the ram is brought to the proper 55 position, the pawl is thrown in and locked. The work is then pressed for a moment and the operator immediately raises the ram by the pawl lock and repeats this light quick pressing until the exact amount of bend is 60 secured.

What I claim is:—

1. In a press, a cast metal frame having a groove in the face thereof, a tension-taking arm secured thereto at the top and extending 65 forwardly of said frame, a bed secured to the

bottom of said frame, and extending forwardly thereof, a tool movably mounted at the extended end of said arm and adapted to exert a tension stress on one side of said frame and a compression stress on the other side of said frame, said arm being of metal having greater elasticity than the cast metal frame so as to yield between the tool and the frame without permanent deformation of the arm and a member secured to said arm and to said bed and placed under tension to compress one side of said frame to relieve said side of tension strain, said member being positioned in said groove.

2. The device of claim 1 in which the arm is of rolled steel, the tool is a ram, and the bed extends parallel to the arm to support the work directly under the ram.

3. The device of claim 1 in which the arm and the bed each consist of two steel members independently bolted to the frame, and the tension member is a steel rod engaging at each end a transverse saddle straddling the two members of the adjacent arm or bed, said rod paralleling one side of the frame.

4. In a press, a ram, a frame supporting said ram, a pawl and ratchet mechanism for operating said ram, means for locking said pawl to said ratchet, and means located approximately midway between the axis of the ram and the far side of the frame for relieving the near side of the frame from the strain incident to the use of the ram as a pressing tool.

5. In a press, a rack ram, a pinion shaft, a pinion on said shaft for operating said rack, a handwheel and a ratchet wheel each fast on the pinion shaft, a lever loosely mounted on said shaft, a pawl pivoted to said lever and engaging said ratchet, and means for locking said pawl to said ratchet whereby movement of the lever in either direction will operate the rack.

6. In a press, a cast metal frame, a pair of steel members extending forwardly from the frame and secured thereto at the top to form an upper arm, a pair of steel members bolted to the frame at the bottom and extending forwardly of the frame to form a bed, a housing secured to the free end of the upper arm, a rack ram slidably mounted therein, a pawl and ratchet mechanism for operating said ram, means for locking said pawl to said ratchet, a support adjustably mounted on the bed for maintaining work in position to be pressed downwardly by said ram and a steel rod binding together said arm and said bed, parallel to the ram and located along the side of the frame proximate to the ram.

In testimony whereof I affix my signature.

ROBERT E. MANLEY.
